UNITED STATES PATENT OFFICE.

JOHN H. WHEELOCK, OF WORCESTER, MASSACHUSETTS, ASSIGNOR TO KLAXON COMPANY, OF NEWARK, NEW JERSEY, A CORPORATION OF DELAWARE.

SOUND-PRODUCING DEVICE.

1,388,986.

Specification of Letters Patent. Patented Aug. 30, 1921.

Application filed December 31, 1917. Serial No. 209,770.

To all whom it may concern:

Be it known that I, JOHN H. WHEELOCK, a citizen of the United States, residing at Worcester, in the county of Worcester and State of Massachusetts, have invented a new and useful Sound - Producing Device, of which the following is a specification.

My present invention relates to diaphragm horns of the type used for loud or long distance signaling, and more particularly to horns wherein wide amplitude swings of the diaphragm are imparted thereto by a thrust member which necessarily has considerable weight, and said thrust member is actuated positively during a part only of the swing of the diaphragm and on the return movement of the diaphragm necessarily acts as a load on the latter. According to modern practice in all horns of this type, the wide effective swings of the diaphragm occur when certain definite speeds are obtained. In such cases, the weight of the thrust member acts to retard, graduate and smooth out the swing movements of the diaphragm, and I have discovered that at speeds where the amplitude of swing of the diaphragm is greatest and the most powerful sound wave is being generated, the note may be too smooth to produce maximum sound effect on the human ear.

My present invention depends upon the discovery that when the diaphragm is thus vibrating with maximum mechanical efficiency, with very disproportionate sound effect on the ear, the volume of sound may be enormously increased by adjusting a perfectly rigid abutment having a rigid face to a point where it barely contacts with the bellying portion of the diaphragm at the extreme limit of its swing, preferably the outward swing which is the one forced by the plunger. In such cases, if a hard metallic abutment rigidly supported is screwed toward the diaphragm, the instant the swinging diaphragm touches it, the volume of sound is tremendously increased, but without any apparent interference with the mechanical efficiency and wide swinging of the diaphragm.

My invention may be more fully understood from the following detailed description thereof in connection with the accompanying drawing in which—

Figure 1 is an end elevation of a horn

showing one embodiment of this invention, 55 and

Fig. 2 is a longitudinal central sectional view of a double horn showing several modifications.

The invention is shown in Fig. 1 as applied to a horn of simple character having a vibrating diaphragm 11 held at its edges by being clamped between two plates 12 and 13 constituting part of the casing of the horn. The diaphragm is shown as vibrated by a thrust member 15 operated by an electromagnet 16 either alternating or intermittent. The above-named features are simply selected from the well-known types of horns, and it is to be understood that this invention is not limited to that particular construction.

The feature of the invention shown in this figure is the attachment to the casing plate 13 or other stationary element of an abutment 17. This is shown in the present instance in the form of a set screw which can be adjusted back and forth to regulate the loudness by contacting with the diaphragm with the required firmness at the outward limit only of its swing, but in commercial manufacture a mere projection can be placed or formed on the casing plate and originally made in the proper location to cause the maximum sound to be produced.

While merely unscrewing the abutment 17 out of range of the diaphragm will usually reduce the sound as much as ordinarily desirable, the device is shown as provided with a deadening screw 18 located on a fixed part of the casing and adapted to engage the diaphragm at a point near its edge or elsewhere. This screw works entirely differently from the screw 17 because ordinarily it is not in use, but when it is to be put in use for deadening the sound it is simply screwed up against the diaphragm and firmly so as to remain in contact therewith and cut down the amplitude of swings of the diaphragm by preventing or partially preventing the vibration of the zone of the diaphragm beyond the screw. It is for this reason that it is located at a distance from the edge but at a greater distance from the center because when used it is still desired to have a part of the diaphragm vibrate so as to produce a deadened sound.

The screw 17 is located near a point of

great amplitude of vibration; in this case, the diaphragm being circular, point of greatest amplitude is located near the center, and the amplitude is sufficient for my purpose 5 even at the point indicated in the drawings.

In operation the abutment 17 is located at, or adjusted to, such a distance from the normal position of the diaphragm that when the diaphragm vibrates it will just touch the 10 end of the screw on each vibration. I have found in practice that under certain conditions this adds immensely to the loudness of sound produced and that the sound produced by vibrating the diaphragm against 15 such a fixed element is so great as to drown out the sound produced by the mere flexing back and forth of the diaphragm itself, although that usually is at least as great as ordinary horns produce. It will be understood further that when the deadening screw 18 is screwed down it so reduces the amplitude of vibration that the diaphragm will not thereafter engage the screw 17, so that this deadening screw reduces the sound in 20 two ways; first, by eliminating the use of the abutment for the time being and leaving only the ordinary vibration of the diaphragm to produce the sound, and second, by decreasing the area and amplitude of vibration of the diaphragm. 25

In the form shown in Fig. 2 most of the parts described in connection with Fig. 1 are present, namely the parts 11, 12, 13, 15, 17 and 18. But two vibrating members or 30 diaphragms 11 are shown and the plunger or floating vibrator is shown having two ends 15^a. They are connected together by an eccentric strap 21 so as to move together. The eccentric strap is operated by a cam 22 35 on a shaft 23 operated by hand or motor (which may be of the direct current type) or by such an operating device as is used on Klaxon horn, for example. The plunger ends 15^a can be guided by guides 24 and always engage the two diaphragms so as to 40 move back and forth with them. The eccentric or cam positively forces the plunger in one direction with the diaphragms and one of the diaphragms preferably is employed 45 as the sole means for forcing it back in the opposite direction.

In this form I have shown the plates 12 and 13 as supporting the diaphragm in a new way. They have substantially circular contacting surfaces 12^a and 13^a between which the extreme edge of the diaphragm is held by screws 25 passing through enlarged holes in the diaphragm and having bushings 26 therein. One of them as 13^a 55 is provided with a wider annular flat surface for receiving the inner edge of the vibrating diaphragm while the other surface on the plate or flange 12^a is narrow. This flange is dished out so that the diaphragm never 60 touches it, but as it vibrates it separates

from the inner portion of the surface of 13^a and apparently impinges upon its corner with enough force to add somewhat to the volume of sound. I find by experiment that the diaphragm actually engages and separates from it, but the motion is so slight that the human eye cannot observe it. This constitutes a circular abutment for the same purpose as the screw 17. 70

I have shown two sound emitting horns 75 30 extending from opposite ends of the device and merging in one horn-shaped mouth 31 to collect the sound and direct it wherever desired.

In operation the rapid rotation of the shaft 80 23 causes the two diaphragms to vibrate without any tapping action from the plunger ends 15^a. This produces sufficient sound in many types and sizes of horns, but it can always be materially increased by bringing 85 the abutment into action as described above.

Although I have illustrated and described only two forms of the invention, I am aware of the fact that other modifications can be made therein by any person skilled in the 90 art without departing from the scope of the invention as expressed in the claims. Therefore I do not wish to be limited to all the details of construction or to the particular types of horn shown, but what I do claim is: 95

1. In a horn, the combination of two parallel diaphragms, a thrust member arranged perpendicularly to the two diaphragms and located between them, and always in contact with both, whereby when moved in one direction the plunger will distort one of the diaphragms and both diaphragms will move with it in both directions, and two abutments having rigid surfaces adapted to engage one diaphragm, one of said abutments 100 tending to prevent vibration of one part and the other to limit the amplitude of swing of another part of said diaphragm. 105

2. A sound producer comprising a pair of parallel diaphragms, a thrust member between them in contact with both, means for moving said thrust member in one direction toward one diaphragm, the other diaphragm being arranged to move simultaneously in the same direction, and circular members 110 having rigid contact surfaces in position to engage the diaphragms throughout a portion only of each vibratory swing. 115

3. In a sound producer, the combination with two plates having plane annular clamping surfaces adjacent to each other, one having a greater width than the other toward the center of the annulus, a diaphragm held between said surfaces, and means for vibrating said diaphragm to engage and separate from the inner edge of said wider surface. 120

4. A sound producer including a diaphragm, a thrust member, means for moving said thrust member in one direction 125 130

with said diaphragm to deflect the latter, means for maintaining said member in contact with said diaphragm during the return movement of said member by said diaphragm, and a circular member having a rigid contact surface in position to engage the diaphragm through a portion only of each vibratory swing.

5. A sound producer including a diaphragm, a thrust member, means for moving said thrust member in one direction with said diaphragm to deflect the latter, means for maintaining said member in contact with said diaphragm during the return movement of said member by said diaphragm, and a pair of stops one adapted to act as a deadener and adjustable to engage with and tend to prevent vibration of a portion of the diaphragm and the other engaging with the diaphragm during a portion only of the swing of the latter to limit the amplitude of vibration of the diaphragm.

6. A sound producer including a diaphragm, a thrust member, means for moving said thrust member in one direction with said diaphragm to deflect the latter, means for maintaining said member in contact with said diaphragm during the return movement of said member by said diaphragm, and an adjustable abutment in the path of movement of the diaphragm and adapted to engage with the diaphragm during a portion only of the swing of the latter and limit the amplitude of swing of the diaphragm.

7. A device of the character set forth in claim 5 in which the stops are adjacent to each other but at different distances from the center of the diaphragm, the first mentioned stop being at the greater distance.

In testimony whereof I have hereunto affixed my signature.

JOHN H. WHEELOCK.
